UNITED STATES PATENT OFFICE

WILLIAM F. RIEGER, OF SALT LAKE CITY, UTAH, ASSIGNOR, BY MESNE ASSIGNMENTS,
TO THE STOKER MATIC CORPORATION, OF SALT LAKE CITY, UTAH, A CORPORATION
OF UTAH

RETORT

Application filed August 27, 1928. Serial No. 302,310.

My invention relates to retorts and has for its object to provide a new and efficient water cooled retort for furnaces, heating plants and boilers which will be economical to operate, 5 easily installed and which will last a long time in service.

A further object is to provide a retort which will not burn out from overheating and one which will eliminate the troublesome feature of clinkers freezing to the outer rim and clogging the tuyère openings and rendering combustion of the fuel difficult or impossible.

A still further object is to provide an air and water cooled retort for heating plants in 15 which the tuyère openings are between the water jackets.

These objects I accomplish with the device illustrated in the accompanying drawings in which similar numerals and letters of reference indicate like parts throughout the several views and as described in the specification forming a part of this application and pointed out in the appended claims.

In the drawings in which I have shown the best and most preferred manner of building 25 my invention Figure 1 is a plan view of the retort with the furnace outlines in dotted lines. Figure 2 is a longitudinal section. Figure 3 is a transverse section. Figure 4 is a 30 sectional view of a modified manner of building the water chamber and the tuyère openings therein. Figure 5 is a modified form of Figure 4. Figure 6 is a modification of the device showing the use of tubular water 35 chambers. Figure 7 is a modification of Figure 6 with the side walls sloping. Figure 8 is a modification of Figure 4 with the side walls shown sloping. Figure 9 is a simplified manner of building the entire retort with 40 tuyère openings shown tapered. Figure 10 is a modification of Figure 8 but with each water jacket made separately and spaced from the next by a wall extension.

In the drawings I have shown the outline of 45 the furnace in dotted lines A, with the main body of the retort as B. The retort is made up of a rectangular shaped body member B having water jackets 1 and 2 around the inner periphery thereof, and with the inner face 50 3 of the retort forming the front side of the

said jackets. Tuyère openings 4 are then cut through the face 3 between the two jackets 1 and 2, to allow passage of air therethrough. The tuyère openings may be rectangular in cross section or any other shape desired for the furnace. In Figures 2, 3, 4, 8 and 10 the water jackets are shown as triangular shaped in cross section while those shown in Figures 6 and 7 are cylindrical and those in Figure 5 are square. The triangular jackets shown in Figures 2, 3, 4, 8 and 10 are made within the air chamber 5 and the front face of the air chamber is made up of the jackets spaced apart either by an integral wall extension as shown in Figure 10 or by welding a sheet of metal 6 across the space between the jackets and forming the tuyère openings therethrough as shown in Fig. 4. The cylindrical water jackets are spaced apart by a flat sheet of metal 7 having the tuyère openings 4 cut therein, and the square water jackets are spaced apart by the front face of the air chamber being made as the front face of the water jackets. The air chamber C is made of four sides of sheet metal connected together 55 with the top closed and air openings 5' therethrough or the top may be left off as shown in Figures 5, 6, 8, 9 and 10, and the sides extended upwardly to form part of the upper part of the air chamber 5. The chamber C and the air chamber 5 are in open communication and may be made integral with the water jackets therein. Below the water jackets and as a top side for the central portion of the air chamber C, I provide a curved semi-circular sheet of metal 10 which is secured to the top of the air chamber at its sides and ends and constitutes the surface over which the fuel is introduced. The fuel screw 14 is mounted in a cylindrical feed pipe 12 and 60 forces the fuel inwardly over the sheet 10 where it is ignited and burned. An air inlet pipe 13 is provided in the front side of the air chamber C through which air may be forced from any desired source. 65

The operation of the invention is as follows:

The fuel is fed into the retort through the pipe 12 by the screw 11 and it is there ignited by the fuel already burning therein or by a 70 75 80 85 90 95 100

wood fire started when the fire is desired. This fuel is forced inwardly and upwardly into the retort. Air is introduced into the air chamber C and into the chamber 5 and out through the tuyère openings 4 to aid in the combustion of the fuel. The air thus introduced is cold and aids in cooling the retort and the water contained in the jackets keeps the inner surface of the retort at such a temperature that the metal will be protected from the heat. The water jackets are connected with a source of water supply or with the boiler which the retort is heating and aid in the heating of the boiler by introducing the hot water or steam therein. The water jackets must have circulating water therein to keep them cool.

Having thus described my invention what I claim as new and desire to secure by Letters 20 Patent is:

1. In a furnace construction of the class described, a retort having a plurality of openings in the walls thereof, an air chamber having its circumscribing wall arranged 25 in spaced relation to the retort walls, and water cooling means projecting into the air chamber from the retort walls, said water cooling means defining water cooled air passages communicating with the openings in 30 the retort walls and constituting cooling means for said openings and walls.
2. In a furnace construction of the class described, the combination of a retort, an air chamber surrounding the same and having 35 its circumscribing wall arranged in spaced relation to the retort walls, said retort walls having a plurality of rows of openings therein, and water conduits carried by and extending about the said retort walls, 40 said conduits defining air passages communicating with the openings in the retort walls and constituting cooling means for said 45 passages and walls.

3. In a furnace construction of the class described, a retort having bottom and side walls, an enclosing air chamber extending around and beneath the retort and having its circumscribing wall arranged in spaced relation to the retort walls, and a plurality of 50 cooling tubes formed on the side walls of the retort in spaced relation to each other and projecting into the air chamber to define air passages therebetween, said side walls having tuyère openings therethrough intermediate 55 the said cooling tubes in communication with the air passages defined by said cooling tubes.

4. In a furnace construction of the class described, a retort having a plurality of rows of openings in the walls thereof, an air chamber surrounding the retort and having its circumscribing wall arranged in spaced relation to the retort walls, and water cooling means formed on said retort walls above and below the openings in said walls and extending 60 into the air chamber, said water cooling

means defining water cooled air passages therebetween in communication with the said openings and constituting cooling means for the retort walls.

5. In a furnace construction of the class described, a retort, fuel feeding means therefor having a curved bottom, side walls extending upwardly therefrom, a cooling jacket formed on the said walls at the top thereof, said walls having tuyère openings therein disposed adjacent to the cooling jacket, a second cooling jacket disposed on the said walls below the first mentioned jacket and adjacent to the tuyère openings, an air chamber surrounding the retort and having its circumscribing wall extending downwardly from the first mentioned jacket in spaced relation to the retort and enclosing the second jacket, said jackets defining air passages therebetween in communication with the said tuyère openings in the side walls and constituting cooling means for said passages and walls, and means for supplying air to the air chamber and tuyère openings.

In testimony whereof I have affixed my 90 signature.

WILLIAM F. RIEGER.
